CLAIM

We claim the ornamental design for a personal computer bezel, as shown and described.

DESCRIPTION

FIG. 1 is an upper right front perspective view of a personal computer bezel wherein the areas shown in broken lines are depicted for illustrative purposes only and do not form any part of the claimed design;

FIG. 2 is a front elevational view thereof, wherein the rear contains no design features;

FIG. 3 a left side elevational view thereof;

FIG. 4 a right side elevational view thereof;

FIG. 5 is a top plan view thereof; and,

FIG. 6 is a bottom plan view thereof.
